UNITED STATES PATENT OFFICE.

HARRY W. WEYMAN, OF PHILADELPHIA, PENNSYLVANIA, ASSIGNOR TO H. A. WEYMAN & SON, INC., OF PHILADELPHIA, PENNSYLVANIA, A CORPORATION OF PENNSYLVANIA.

BANJO.

Application filed August 15, 1921. Serial No. 492,420.

To all whom it may concern:

Be it known that I, HARRY W. WEYMAN, a citizen of the United States, residing at Philadelphia, in the county of 5 Philadelphia and State of Pennsylvania, have invented new and useful Improvements in a Banjo, of which the following is a specification.

My invention relates to new and useful 10 improvements in banjos and other similar musical instruments, and has for its object to improve the construction thereof so as to be neat in appearance and strong and durable.

15 Another object of the invention is to provide means whereby the quality of the musical production will be improved.

A further object of the invention is to 20 provide a musical instrument of the class mentioned having a sound amplifier produced from the rim thereof.

A still further object of the invention is 25 to so construct the body of the musical instrument as to eliminate the protruding brackets, the fillister screw passing through a bore in the rim projecting into a counter-bore in which the adjusting nuts are housed.

With these ends in view, this invention 30 consists in the details of construction and combination of elements hereinafter set forth and then specifically designated by the claims.

In order that those skilled in the art to 35 which this invention appertains, may understand how to make and use the same, I will describe its construction in detail, referring by numerals to the accompanying drawing forming a part of this application, in which:—

40 Fig. 1, is a front elevation of a banjo embodying my improvements.

Fig. 2, is a side elevation thereof.

Fig. 3, is an enlarged fragmentary sectional view of the rim illustrating the relation of the component parts thereto the fillister screw being shown in elevation.

Fig. 4, is a fragmentary edge view of the rim.

Fig. 5, is a transverse sectional view, on 50 a reduced scale, of the rim.

In carrying out my invention as here embodied, 2 represents a wooden rim constructed from one or more pieces as is well known in the manufacture of musical instruments

and this rim has a groove 3 formed in its upper outer edge and in the case of a banjo is annular in shape. In this recess is located the ring 4 on which rests the parchment head 5, the latter being held in place by the hoop 6 which latter is fastened in position and adjusted to produce the desired tension upon the head by means of fillister screws 7 the latter passing through bores 8 formed in the wood rim 2 and projecting into the counterbore 9 formed in the lower edge of the rim and communicating with the aforementioned bores. In the counterbores are located the nuts 10 having threaded connection with the fillister screws and if found desirable suitable washers 11 may be interposed between the inner ends of the nuts and the end walls of the counterbores.

This construction eliminates the brackets ordinarily used on musical instruments of this character in conjunction with the fillister screws so that the exterior of the rim 2 forming a part of the body presents a smooth surface thereby eliminating one of the objectional features in banjos, namely, the protruding brackets which catch in and snare the clothing of the musician. Further such a construction gives to a musical instrument a much neater appearance than one having a great number of protruding brackets and as said brackets are likely to be turned from one side to the other, twisted or broken off the elimination thereof greatly strengthens the construction of the body.

The rim 2 of the body forms an amplifier by which the musical vibrations are amplified and modified in tone to give mellowness to the vibrations, and said amplifier is produced by the outwardly diverging inner surfaces of the wood rim 2 as indicated at 12 so that said amplifier is in the shape of a truncated cone with the smaller end adjacent the parchment head 5.

To the body of the musical instrument is fastened in the well known manner the ordinary neck 13 carrying the head 14 and 100 provided with suitable pegs or keys 15.

Of course I do not wish to be limited to the exact details of construction as herein shown as these may be varied within the limits of the appended claims without departing from the spirit of my invention.

Having thus fully described my invention, what I claim as new and useful is:—

1. A musical instrument comprising a rim having its inner surface beveled outwardly provided with openings therethrough, a head disposed across said rim 5 adjacent the smaller inner diameter thereof, a hoop to engage said head, fillister screws coacting with said hoop and projecting into the openings, and means also within said openings to engage the screws for adjusting the same.
2. A musical instrument comprising a wood rim having an exterior groove and provided with communicating bores and counterbores and further having its inner 15 surface beveled outwardly producing a truncated cone shaped amplifier, a ring dis-

posed within the groove, a parchment head disposed across the smaller end of the amplifier and engaging said ring, a hoop for holding the head on said ring, fillister 20 screws coacting with said hoop with portions thereof passing through the bores and projecting into the counterbores whereby said portions are entirely housed within the rim and nuts located in the counterbores 25 and having threaded engagement with said screws to adjust the latter, said nuts also being entirely housed within the rim.

In testimony whereof, I have hereunto affixed my signature.

HARRY W. WEYMANN:
